INVENTOR.

C. H. TODD.

BY HIS ATTORNEY.

James F. Williams

UNITED STATES PATENT OFFICE.

CHARLES H. TODD, OF NEW RICHMOND, WISCONSIN.

VIOLIN-SOUND-POST SETTER.

Application filed August 17, 1921. Serial No. 492,876.

To all whom it may concern:

Be it known that I, CHARLES H. TODD, a citizen of the United States, residing at New Richmond, in the county of Saint Croix and State of Wisconsin, have invented certain new and useful Improvements in a Violin-Sound-Post Setter; and I do hereby declare the following to be a full, clear, and exact description of the invention, such as will enable others skilled in the art to which it appertains to make and use the same.

This invention relates to a device adapted to perform the measuring operations for and to place in position the sound posts provided between the upper and lower walls of a violin body. These sound posts which comprise small cylindrical members are placed after the violin body is assembled and it has been a tedious and difficult job to properly measure and place the same in position.

It is an object of this invention to provide an extremely simple device by which the required length of the post may be determined and by means of which the posts may be held and quickly and easily placed in position.

It is a further object of the invention to provide the device with a clamping means for holding the post, comprising a flexible member, by means of which the posts can be readily released from the clamping device.

These and other objects and advantages of the invention will be apparent from the following description made in connection with the accompanying drawing in which like reference characters refer to the same parts throughout the different views, and in which

Fig. 1 represents a perspective view showing the use of the device on a violin;

Fig. 2 shows the device in side elevation as used with a violin;

Fig. 3 shows the device as used to measure the length of the sound post;

Fig. 4 is a horizontal section taken on the line 4—4 of Fig. 2, looking in the direction of the arrows; and

Fig. 5 is a partial plan view showing a modification.

Referring to the drawings, in Fig. 1 is shown a portion of a violin body *a* comprising the strings 1, the bridge 2 and the usual curved openings or slots 3 in the top thereof. The sound post 4 is placed on the inside of the violin body adjacent the bowed portion of the strings and extends from the top to the bottom of said body, being glued or otherwise held permanently in position.

The device of this invention comprises a handle portion 5 in which is rigidly fastened a small rod 6. This rod is bent downwardly near its end and has a forwardly projecting portion 6^a extending substantially parallel to its main body portion. A semi-cylindrical sleeve 7 is soldered or otherwise suitably secured at its convex side to the end of the portion 6^a, said portion being secured to the sleeve at substantially its vertical central portion. The portion 6^a has a hole formed transversely therethrough adjacent the sleeve 7 and a cord or string member 8 passes through said hole and has a knot on its end to prevent its withdrawal therethrough. The other end of the member 8 is secured to a ring 9. The device comprises a measuring post comprising a threaded sleeve 10 into which screws a threaded shank 11^a of a head 11.

In the use of the instrument, to determine the required length of the sound post, the sleeve 10 is placed in the sleeve 7 and the cord 8 wrapped one or more times around said sleeves, as shown in Fig. 3. The post and rod 6 can then be introduced through the slot 3 of the violin. By adjusting the head 11 until the post just fits between the top and bottom of the violin body, the exact length of post required can be determined.

In placing the sound post proper into the violin body, the post 4 is placed in the sleeve 7 in the same manner as was the post 10, and as shown in Fig. 2. The member 8 is then wrapped one or more times around the post and sleeve and this member held tight by one finger engaging in ring 9, as shown in Fig. 1. The post is thus rigidly and firmly supported in the holder and can be introduced through the slot 3, as shown in Fig. 1. The post is moved to the desired position between the top and bottom portions of the violin body and when placed in the desired position can be permanently secured. After the post has been located the ring 9 is released and the handle 5 moved away when the cord 8 and ring 9 will be loosely drawn out of the violin body around the post without disturbing the same.

Fig. 5 shows a convenient method of securing the cord or string used. In this form, the cord is formed with two strands 8^a, the loose ends of which are passed through the portion 6^a of rod 6 and knotted so that it cannot be withdrawn therethrough. The ring 9^a is held by the two

strands by simply passing the loose ends through the bight or end loop of the strands thus forming a holding loop for the ring. The two strands of the cord function just 5 as the one strand previously described.

From the above description it will be seen that applicant has provided a very simple and efficient tool by which the sound post can be easily and quickly measured and 10 placed in position. The device has proven very efficient in actual practice and been very successful in its use.

It will, of course, be understood that various changes may be made in the form, 15 details and proportions of the parts without departing from the scope of applicant's invention, which, generally stated, consists in the matter shown and described and set forth in the appended claims.

20 What is claimed is:

1. A sound post placing device comprising a handle, a member extending therefrom and having a holding means including a flexible member at the end thereof adapted 25 to be introduced into a violin body through the usual opening in the top thereof.

2. A sound post placing device comprising a handle, a member extending therefrom and having a clamping means at one end including a rigid member having a concave surface adapted to extend longitudinally of the post, and a flexible member co-operating therewith.

3. The structure set forth in claim 2, the 35 flexible member being attached at one end adjacent the said rigid member and extending to said handle portion and having a holding means attached thereto at its other end.

4. A sound post placing device comprising 40 a handle, a rod extending therefrom having its end portion bent into a lower plane than the portion connected to the handle, a semi-cylindrical sleeve secured to the end of the rod, a flexible cable secured adjacent said 45 sleeve, and a holding means on the end of the cable.

5. A sound post placing device comprising 50 a handle portion, a wire rod secured thereto and extending therefrom having its end portion parallel to but disposed in another plane from the portion secured to the handle, a rigid clamping member rigidly secured to the end of the rod, and a flexible cable secured to the rod adjacent said clamping 55 member and having a holding means at one end.

6. A sound post placing device comprising 60 a handle, a wire or rod extending longitudinally therefrom and bent at substantially a right angle at some distance from said handle and again bent at a substantially right angle to extend parallel to the portion adjacent the handle, and a clamping means on the end of said wire or rod.

7. The structure set forth in claim 6, said 65 clamping means including a segment of a hollow cylinder having its convex surface attached to the end of the rod with the longitudinal axis of the segment normal to the axis of said rod.

8. The structure set forth in claim 7, a 70 flexible member being attached to the end of a wire or rod adjacent said segment and extending to the handle portion.

In testimony whereof I affix my signature.

CHARLES H. TODD.
